UNITED STATES PATENT OFFICE.

ALEXANDER P. WHITE, OF CALDWELL, NEW JERSEY, ASSIGNOR TO THE GENERAL FIRE-PROOFING COMPANY, OF YOUNGSTOWN, OHIO, A CORPORATION OF OHIO.

REINFORCING-FRAME AND CEMENTITIOUS CONSTRUCTION.

No. 883,768.

Specification of Letters Patent.

Patented April 7, 1908.

Application filed September 27, 1906. Serial No. 336,435.

To all whom it may concern:

Be it known that I, ALEXANDER P. WHITE, a citizen of the United States, and resident of Caldwell, Essex county, New Jersey, have 5 invented certain new and useful Improvements in Reinforcing-Frames and Cementitious Constructions, of which the following is a specification, accompanied by drawings.

This invention relates to reinforcing frames 10 suitable for embodiment in concrete and other masonry constructions and to cementitious constructions, and the objects of the invention are to improve upon the construction of such reinforcing frames, render them 15 more suitably adapted to meet the special requirements of different constructions, and enable the parts of the frames to be readily and quickly assembled.

Another object of the invention is to 20 cheapen the cost of manufacture without impairing the strength of the parts, and improve on cementitious constructions.

Further objects of the invention will hereinafter appear and to these ends the invention 25 consists of a reinforcing frame substantially as hereinafter more fully described and claimed in this specification and shown in the accompanying drawings, in which,—

Figure 1 is a side elevation of a portion of a 30 reinforcing frame embodying the invention; Fig. 2 is a side elevation of a double form of reinforcing frame; Fig. 3 is a side elevation of a portion of the frame shown in Fig. 2, having a modified form of slat; Fig. 4 is a detail side elevation showing a twisted slat. 35 Fig. 5 is an end view of a truss embodying the invention. Fig. 6 is a side elevation partly broken away and partly in section of a continuous concrete reinforcement; Fig. 40 7 is a partial plan view of Fig. 6.

Referring to the drawings, A represents a longitudinal base member which may be a metallic rod or bar of any suitable cross section, in this instance a bar square in cross section being shown by way of illustration. Connected to the base member A by means 45 of slats or tie pieces B is another or upper longitudinal member C, shown extending substantially parallel to the base member A 50 in Fig. 1 in order to illustrate the invention.

In order to connect the members A and C, slats B of sheet metal are provided, and according to this invention each slat is slit at the ends at D longitudinally as shown the 55 strips of metal at the sides of each slit being

bent outwardly away from each other out of the plane of the body portion of the strap to form eyes or apertures for the reception of the main members of the frame and the members A and C are passed through said 55 eyes or apertures. The metal of the slats B is then pressed or otherwise formed tightly around the members A and C, thereby forming a rigid reinforcing frame.

The slats or tie pieces B may extend at 60 right angles transversely across the members A and C, or else they may be arranged at other angles thereto as shown in Fig. 1, and these tie pieces may all be parallel or not as desired.

In Fig. 1, the broad sides of the slats B are arranged outwardly, while in Fig. 3 each slat is given a half turn about its longitudinal axis, thereby bringing the narrow edges of the slat outwardly. The metal of the slat is 65 preferably twisted tightly about the longitudinal members A and C, thereby clamping the slat tightly to said members. In Fig. 4 each slat is twisted several times about its longitudinal axis, making a very firm and 70 rigid construction and clamping the slats tightly to the longitudinal members.

It is well known that the stresses in a concrete beam or girder follow certain lines. Particularly the tensile strains, beginning at 80 the top end of a girder or beam will follow a line descending as it approaches the center of the beam or girder and then ascends as it approaches the opposite end. It thus follows that the greatest tensile strain is at the 85 bottom of the central or middle portion of the beam or girder. In Fig. 2 a reinforcing frame is shown which is designed to withstand the strains met with in building constructions. In this instance the base member A 90 is connected to the upper members E and F by means of the slats G, but as shown the upper members E and F slant upwardly from the center and the slats or tie pieces G necessarily increase in length from the center 95 towards the ends of the reinforcing frame. The slats or tie pieces G in one side of the center may all extend parallel to each other as shown, or they may be arranged in any other desired manner. These slats G may 100 also be perfectly flat as shown, or else they may be twisted as in Figs. 3 and 4.

In Fig. 5 an end view of a reinforcing truss is shown in which there are three longitudinal members A A and C connected by the slats 110

or tie pieces B, illustrating in what manner modifications of the reinforcing frame may be constructed.

- In Figs. 6 and 7 of the drawings I have shown a form of construction embodying my invention adapted for girder and beam frames for concrete reinforcement, so that a frame may be extended from one bay to the adjacent bay, making a continuous reinforcement. In the example shown the construction comprises two pairs of like frames or trusses, the frames of each pair being placed in parallel relation to each other and crossing the other pair midway of their length. Each of the four frames may be described as formed of two frames shown like that of Fig. 2, although they may be like Fig. 1 placed end to end the central upper longitudinal members being integral. H designates this central upper member consisting of a middle depressed portion I and descending ends K.

L designates one of the outer upper members which slants downwardly from its outer end as do the members E and F of Fig. 2.

M, M are the base bars or members, each of which extends under an end of the central upper member H and under the outer upper members L the inner ends of these two base members M are spaced apart from each other for a purpose which will hereafter appear. All of the upper and lower members are secured together by slats or tie frames G as already described. Two of these reinforced frames are placed side by side and preferably spaced apart from each other as shown in Fig. 7 of the drawings. Two other frames like these, excepting that the depression I in the central upper members is omitted, are then placed across these, the depression I in one pair of the frames permitting the four frames to lie in the same horizontal plane. A mass of concrete indicated at O embeds the cross frames and completes the structure.

While I have shown the cross frames or trusses as arranged in pairs it is obvious that the number of frames extending in each direction may be varied as the exigencies of the work require.

Obviously some features of this invention may be used without others and the invention may be embodied in widely varying forms, therefore, without limiting the invention to the devices shown and described, and without enumerating equivalents, I claim and desire to obtain by Letters Patent the following:

1. A rigid reinforcing frame, comprising main members and flat connecting metal slats, the slats having near each end a slit, the metal on each side of the slit being pressed in opposite directions to form an eye through which the main members pass, the walls of the eyes closely embracing the main members.

2. A rigid reinforcing frame, comprising main members and twisted flat connecting metal slats, the slats having near each end a slit, the metal on each side of the slit being pressed in opposite directions to form an eye through which the main members pass, the walls of the eyes closely embracing the main members.

3. A rigid reinforcing frame, comprising a main base member, longitudinal members, each extending at an angle to said base member, and flat connecting metal slats, the slats having near each end a slit, the metal on each side of the slit being pressed in opposite directions to form an eye through which the main members pass, the walls of the eyes closely embracing the main members.

4. A rigid reinforcing frame, comprising two main members diverging from each other, and flat connecting metal slats, the slats having near each end a slit, the metal on each side of the slit being pressed in opposite directions to form an eye through which the main members pass, the walls of the eyes closely embracing the main members.

5. A rigid reinforcing frame, comprising two main members diverging from each other, and twisted flat connecting metal slats, the slats having near each end a slit, the metal on each side of the slit being pressed in opposite directions to form an eye through which the main members pass, the walls of the eyes closely embracing the main members.

In testimony whereof I have signed this specification in the presence of two subscribing witnesses.

ALEXANDER P. WHITE.
